US0D1082006S

(12) **United States Design Patent** (10) **Patent No.:** **US D1,082,006 S**
(45) **Date of Patent:** **** Jul. 1, 2025**

(54) **IMPLANTABLE CARDIAC DEVICE**

(71) Applicant: **Impulse Dynamics NV**, Willemstad
(CW)

(72) Inventors: **David Prutchi**, Voorhees, NJ (US);
Jason Meyers, Haddonfield, NJ (US)

(73) Assignee: **Impulse Dynamics NV**, Willemstad
(CW)

(**) Term: **15 Years**

(21) Appl. No.: **29/827,136**

(22) Filed: **Feb. 17, 2022**

(51) **LOC (15) Cl. 24-02**

(52) **U.S. Cl.**

USPC **D24/167**

(58) **Field of Classification Search**

USPC D24/112, 127-129, 164, 166-167,
D24/169-170, 184, 186, 231; D10/46, 75

CLAIM

The ornamental design for an implantable cardiac device, as shown and described.

DESCRIPTION

FIG. 1 is a front view of an implantable cardiac device, showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The oblique lines in the drawings indicate transparency.
